FRANCE.

TWO-STROKE INTERNAL-COMBUSTION ENGINE.

Application filed March 30, 1925, Serial No. 19,344; and in France April 7, 1924.

The present invention relates to two-stroke internal combustion engines (as distinct from four-stroke engines with forced induction, using the crank case compression for obtaining the necessary air pressure) of the type in which air alone is compressed in the crank case and receives its charge of fuel during its passage through the transfer passage.

10 In internal combustion engines of the above type it is customary to allow the pressure produced in the crank case to act upon the fuel in the float chamber in order to equalize the pressure in the float chamber 15 and the transfer passage.

Now according to our invention, the pressure obtaining in the fuel tank, as well as in the float chamber and in the transfer passage is equalized by providing a conduit 20 from the crank case to the fuel tank and a second pressure conduit from the top of the fuel tank to the top of the float chamber, the usual fuel pipe being, of course, also provided between the fuel tank and the bottom 25 of the float chamber. The pressure is also equalized between the cylinder and the other parts when the transfer port is uncovered by the piston, so that a static equilibrium of pressure exists at all times between the float 30 chamber and the crank case and that, consequently, the spraying action of the nozzle takes place due to the suction of the working cylinder and the dynamic depression caused by the flow of air around the nozzle as is the 35 case in the common carburetor type.

The appended drawings show by way of example an embodiment of the invention. The figure is a transverse section of a cylinder of the said sprayer and of the float chamber 40 supplying the same.

Each cylinder 1 of the engine comprises the known inlet port 2, and exhaust port 3 which are opened at the end of the expansion stroke by the piston 4 whose closed end comprises a deflector 5, known per se; 6 is the ignition element, for example the usual 45 sparking plug. A closed crank case E constitutes a closed compression chamber 7 which communicates directly with the end of 50 the cylinder opposite the work chamber C.

According to our invention, an automatic valve 8 provides for an admission of air from the exterior into the crank case during the ascent of the piston, and a conduit 9 connects

the chamber 7 of the crank case with the work chamber C of the cylinder, said conduit being provided with suitable means for bringing therein the solid, liquid or gaseous fuel at the moment when (the inlet port 2 being opened by the piston at the end of the down stroke) the air which is compressed in 7 proceeds into the work chamber C through the conduit 9. A closing device 10 provided with the control handle *m* serves to regulate the flow section S between the conduit 9 and the inlet port 2.

In the present example, the liquid fuel is supplied by a sprayer 11 disposed coaxially in the conduit 9; said sprayer is supplied through the conduit 12 by the float chamber 13 which is in turn supplied, through the medium of the pipe 14 and the known automatic needle valve 15, by the fuel tank 16; herein the outlet O of the sprayer opens within the closing device 10 which has the form of a hollow cock plug. Suitable piping 17, 17' connects the chamber 7 of the crank case E with the upper part of the tank 16 and with the top of the float chamber 13. In the form of construction herein represented, the sprayer 11 is of the single type, and the section of its outlet O may be adjusted by means of the rod 18 which is movable lengthwise by suitable controlling means, not shown. Obviously, we may employ any other type of simple or complex sprayer as desired.

The operation is as follows. After the explosion and during the expansion stroke (down stroke), the piston compresses in the chamber 7 of the crank case the air which has been withdrawn through the valve 8. Due to the piping 17 and 17', the fuel in the tank 16 and in the float chamber 13 will be placed in equilibrium, as to pressure, with the air surrounding the sprayer 11. When the piston is at the bottom of the stroke, the burnt gas is discharged through the port 3 in the known manner and the inlet port 2 will now be opened; the air compressed in the chamber 7 will become charged with fuel as it flows around the outlet O of the sprayer, and the carburetted mixture will proceed through the port 2 into the work chamber C. The piston now rises, thus closing the ports 3 and 2, and it compresses the carburetted mixture in the chamber C in the known manner and withdraws fresh air through

the valve 8 into the chamber 9, this air serving for the supply of the cylinder during the succeeding stroke.

It should be observed that in this manner 5 the explosive gas is formed only when it is admitted into the cylinder, and it will not enter the crank case, so that the several parts of the engine can be lubricated as in the four-stroke engines.

10 We will not depart from the principle of the invention by replacing the sprayer for the liquid fuel feed by other means suitably disposed for supplying a solid, liquid or gaseous fuel to the conduit 9, provided the fuel 15 is supplied only while the air compressed in the crank case is flowing in the conduit 9 towards the cylinder C, nor will the said principle be departed from by modifying the throttle 10 or by placing it in another 20 position relatively to the means for feeding the fuel.

We claim:

1. A two-stroke internal combustion engine of the type set forth, in which the air 25 is compressed in the crank case during the working stroke and, at the end of this stroke at the moment of the admission, passes from the crank case into the explosion chamber of the cylinder, comprising an air inlet 30 automatic valve disposed to let enter the atmospheric air into the crank case during

the return stroke, a fuel conduit leading from the fuel tank to the bottom of the float chamber, a conduit for equalizing the pressure between the fuel tank and the float 35 chamber, a conduit for equalizing the pressure between the crank case and the fuel tank, both said conduits for equalizing the pressures between the fuel tank and the float chamber and between the crank case and the 40 fuel tank respectively being distinctly separate from each other, whereby the equilibrium between said fuel tank and said float chamber is obtained.

2. A two-stroke internal combustion engine of the class described, comprising an air inlet automatic valve disposed to let enter the atmospheric air into the crank case during the return stroke, a conduit leading from the crank case to the upper part of the fuel supply tank, a conduit leading from the fuel tank to the lower part of the float chamber to feed a spray nozzle provided between the crank case and the combustion chamber of the cylinder, and a conduit leading directly 50 from the upper part of the fuel supply tank to the upper part of the float chamber.

In testimony whereof we have hereunto set our hands.

EMILE DUTEL.

JEAN MARC PERDONCINI.
